UNITED STATES PATENT OFFICE.

EVERETT R. BURTNELL, OF LOS ANGELES, CALIFORNIA, ASSIGNOR, BY DIRECT AND MESNE ASSIGNMENTS, TO THE AUTOMOTIVE VALVES CORPORATION, OF RENO, NEVADA, A CORPORATION OF NEVADA.

INTERNAL-COMBUSTION ENGINE.

Application filed December 20, 1926. Serial No. 155,869.

My invention relates to two stroke cycle internal combustion engines, and the principal objects of my invention are, to provide in a two stroke cycle internal combustion engine a pair of auxiliary pistons to the working piston of a combustion chamber. To adapt one only of the auxiliary pistons to a valve function, the character of the valve function being charge admission and to employ the second auxiliary piston to counterbalance the admission valve piston in reciprocatory inertia and internal combustion pressure counterdrive influence.

In any case of a two stroke cycle engine wherein a supercharge induction of fresh fuel charge over the range of straight scavenging and initial combustion chamber volume of atmospheric value is desired, some means of providing a fresh charge admission passage communication between the source of fresh charge pumping and the combustion chamber after the exhaust ports of the combustion chamber have been closed must be devised. A piston of conventional form provides the desirable structure for adaption to the function of valving the admission communication registration and cutoff in so far as the valving is concerned. However in order to cause the admission communication to remain in registration after the exhaust ports have been closed in an engine wherein the exhaust ports are formed in the wall of the working cylinder and the working piston provides the necessary and usual exhaust port cutoff, the crank pin to which the piston valving the admission ports is connected must be relatively disposed laterally rotatively with respect to the position of the main crank pin to which the working piston which is adapted to the exhaust port cutoff is connected.

This arrangement of crank pin relationship develops an undesirable opposed driving influence to the cranks from internal pressures, since the working piston necessarily must be of greater stroke sweep displacement than the stroke sweep displacement of the admission valve piston, the compression clearance chamber common to the working piston and admission valve piston will be of the least displacement at the moment the working piston reaches head end dead center, with a corresponding working piston crank pin position of head end dead

center and to accomplish a desirable admission communication registration lag of cutoff, over the exhaust port cutoff, the crank to which the admission valve piston is attached would be in a relative rotative position substantially 40° before head end dead center, the admission valve piston being the corresponding stroke travel distance before head end dead center.

Obviously the combustion must occur at the moment of the maximum compression pressure in the clearance chamber which maximum is attained when the clearance chamber displacement is of a minimum resulting from the working piston being in a most headwardly position of its stroke.

This being the case, a driving influence will be transmitted to the rotary parts of the engine in direct proportion to the square of the admission valve piston and the ratio of its stroke relative to the square of the working piston, its stroke and the number of degrees the crank to the admission valve piston is arranged laterally rotatively with respect to the rotative position of the crank to which the working piston is connected.

Therefore, it is the object of my present invention to provide a pair of auxiliary pistons to a given combustion chamber designed to function in two stroke cycle time, to adapt one of the said auxiliary pistons to the admission valve purpose, to provide the two auxiliary pistons of exact form, weight and dimension, facilitating ease of manufacture, interchangeability.

The inertia force developed by the reciprocatory movement of either of the two auxiliary pistons being equally countered by the reciprocatory inertia force of the other, the arrangement of the pair of auxiliary pistons adjacent and axially parallel permits the reduction of the couple between the plane of the respective reciprocatory forces.

I propose to arrange the two crank pins to which a given pair of auxiliary pistons of one combustion chamber are connected substantially 180° apart, hence, the pair of auxiliary pistons being of exactly the same dimension in every respect the pressure influence transmitted to the crank shaft will be equal and opposed. When combustion occurs and internal driving pressure is developed on the head area of the respective pistons, the only effective driving medium

will be the area of the working piston since, if the one of the two auxiliary pistons which is adapted to the admission valve purpose has a relative crank pin position 40° before head end dead center, the crank position of the other of the two auxiliary pistons to a given combustion chamber will be 40° before crank end dead center.

The advantages of the conventional form 10 of piston for admission valve use in a two stroke cycle engine are manifold; most important of merit being, its relative lightness corresponding to the ratio of port area provided, the simplicity of its structure, the 15 ease by which it can be successfully lubricated from the oil vapors present in the crank case of the engine when in operation, the design of cylinder block it permits tending to make compactness possible, the minimum weight it develops in movement acceleration facilitating high engine rotation acceleration and the substantial ratio of skirt area corresponding to the head area which contacts the heat volume eliminates the problem 20 of heat convection from the valve member in a two stroke cycle internal combustion engine, wherein a high frequency of heat periods are developed by high speed two stroke cycle operation.

25 Fig. 1 is vertical section taken transversely of the engine, the cutting line being stepped and intersecting the axes of the working cylinder and the one of the auxiliary piston cylinders which is adapted to the admission 30 valve function.

Fig. 2 is a cross sectional view of the engine on the line 2—2 of Fig. 1.

Fig. 3 is a vertical longitudinal section taken on line 3—3 of Fig. 2, the cutting line 40 intersecting the axes of the pair of auxiliary pistons and respective cylinders.

Fig. 4 is a vertical section transversely of the engine taken on line 4—4 of Fig. 2, indicating the crank relationship of the working 45 piston crank and the one of the two auxiliary piston cranks which auxiliary piston is adapted to admission valve function.

Fig. 5 is a vertical section transversely of the engine taken on line 5—5 of Fig. 2, indicating the relationship of the working piston 50 crank and the one of the two auxiliary piston cranks which auxiliary piston is adapted to provide counterinfluences to the other of the pair of auxiliary pistons.

Fig. 6 is a diagrammatic view illustrating the diametrically opposed position of the 55 two crank pins to which the pair of related counterbalancing auxiliary pistons are connected.

Referring by numerals to the accompanying drawings, 10 designates a cylinder block, to which a cylinder head 11 is attached, supporting the cylinder block is a crank case 12, a working cylinder 13 is formed in the cylinder block, a pair of axially parallel auxil-

iary piston cylinders 14 and 15 are formed in the cylinder block.

An auxiliary piston 16 is arranged for reciprocatory movement within the cylinder 70 14, a second auxiliary piston 17 is arranged for reciprocatory movement within the cylinder 15, a working piston 18 is arranged for reciprocatory movement in the working cylinder 13.

A crank shaft 19 is arranged in the crank 75 case 12, a crank pin 20 is formed of the crank shaft, a connecting rod 21 provides the usual attachment between the working piston 18 and the crank pin 20.

An auxiliary crank shaft 22 is suitably 80 journaled in the crank case, two crank pins 23 and 24 are formed of the auxiliary crank shaft, the crank pin 23 being disposed substantially diametrically opposite the crank pin 24.

Connecting rods 25 and 26 are employed in the usual manner connecting the auxiliary pistons to the auxiliary shaft 22.

A one to one timing drive is indicated by numerals 27 and 28 on Fig. 1, illustrating 90 the rotation relativity between the crank shaft 19 and the auxiliary crank shaft 22. It is to be understood that the pair of auxiliary pistons to a given combustion chamber may be actuated by direct connection with 95 the main crank shaft if desired without departing from the spirit of the invention.

A combustion chamber compression clearance 29 is formed in the cylinder head and joins the cylindrical chambers of the working cylinder and the two auxiliary piston cylinders into one common chamber.

A series of fresh charge admission ports 30 are formed in the wall of one cylinder only of the pair of auxiliary piston cylinders, a 105 fresh charge passage communicating duct 31 extends around the said auxiliary piston cylinder having the admission ports, the said admission ports are formed in an annular row the plane of which row is at right angle 110 to the axis of the respective cylinder and the fresh charge passage communicating duct 31 being formed in communication with each of the admission ports of the annular row.

An ignition device 32 is screwed into a threaded aperture 33, preferably located in the cylinder head and in a position which will facilitate the sparking terminals protruding the wall of the combustion chamber directly headward of the one of the auxiliary 120 piston cylinders in which is formed the fresh charge admission ports.

An exhaust port 34 is formed in the wall of the working cylinder 13.

A fresh charge induction blower 35 is arranged in passage communication with the fresh charge communicating passage 31 of the cylinder block by a discharge pipe 36.

A fuel mixing device 37 is suspended from the blower. Any suitable blower may be 130

used which will supply an induction force for the admission of fresh charge into the combustion chamber.

It will be seen by Fig. 1, that the working piston is in a position after crank end dead center with the working crank pin 20 substantially 40° after crank end dead center, the corresponding location of the auxiliary crank pin 23 to which the one of the auxiliary pistons of the auxiliary cylinder having the admission ports is connected is substantially in a position of crank end dead center, relatively 40° late rotatively with respect to the position of the working crank. This crank relationship will permit the admission ports being registered and cut-off with the combustion chamber later than the exhaust ports.

To counter the driving effect, anti-rotatively of the late auxiliary crank pin, I provide a second auxiliary piston with crank pin disposed diametrically opposite the crank pin to which the auxiliary piston of the cylinder having the admission ports is connected.

The operation of my improved internal combustion engine is as follows:

Assuming the reciprocatory and rotary parts to be in the position as illustrated in the accompanying drawings, the working piston moving headwardly away from crank end dead center, at this moment the head of the said piston crosses the plane of the headward edge of the exhaust ports, cutting off exit passage communication between the exhaust ports and the combustion chamber.

The auxiliary piston adapted to the auxiliary cylinder of which cylinder is formed the admission ports is in the position of crank end dead center, the admission ports being fully open to the combustion chamber. At this moment the second auxiliary piston is in a position of head end dead center.

As the working piston moves headwardly, the admission port auxiliary piston also moves headwardly to a position with relative crank pin substantially 40° after crank end dead center at which moment the crank pin to which the second auxiliary piston of the auxiliary cylinder having no ports is connected is in the position substantially 40° after head end dead center, balancing the first auxiliary piston, and the crank of the main shaft to which the working piston is connected will be in a rotative position substantially 80° after crank end dead center.

At this moment the head edge of the auxiliary piston of the auxiliary cylinder having the admission ports will pass headwardly beyond the plane of the headward edge of the admission ports, cutting off inlet passage communication with the combustion chamber. Further movement of the working piston and the one of the auxiliary pistons developing compression of the fresh

charge in the compression clearance of the combustion chamber. It will be understood that the stroke sweep of the working piston only is productive of compression since the two auxiliary pistons, one of which is adapted to the admission valve function, are continuously moving in opposite direction their respective stroke sweep displacement being balanced thereby.

Upon the arrival of the working piston at head end dead center, compression being complete, ignition will take place, combustion following, the expansion following combustion driving the working piston crank-wardly through the expansion cylinder. At the moment the working piston is at head end dead center and the time initial combustion is caused to occur the crank pin to which the auxiliary piston adapted to admission port valve function will be in a relative position substantially 40° before head end dead center, the relative position of the other crank pin to which the other of the two auxiliary pistons is connected being substantially 40° before crank end dead center.

Thus it will be understood that the pressure rise in the combustion chamber resulting from combustion of the compressed fresh gaseous mixture will be ineffective in the development of any net power transmission to the rotary element to which it is mechanically associated in either direction, clock or anti-clockwise relative to rotation, the auxiliary piston crank pins being oppositely disposed, balance both, the reciprocatory inertia forces and the piston areas, which piston areas contact the internal pressure.

With further crankward movement of the working piston, the head edge of the said piston will pass crankwardly beyond the plane of the head edge of the exhaust ports, establishing thereby exit passage communication between the exhaust passage and the combustion chamber and providing an outlet for the release of the spent products of combustion expanded in power development within the combustion chamber.

Since the exhaust and admission ports respectively are of a height axially with respect to the respective cylinders of which the said ports are formed of stroke movement respective to each piston corresponding to 40° of crank rotative movement to or from crank end dead center it is evident that the admission ports will not be opened to the combustion chamber until the exhaust ports have been open for a duration of time corresponding to 40° of crank rotative movement, also the admission ports will not be closed until the exhaust ports have been closed for a period of time corresponding to 40° of crank rotative movement.

It is to be understood that the timing relation between the respective crank pins as

described is presented to provide a specific example of the working combination of parts and clearly describe the function.

The relative crank positions may be changed as may be desired to provide a different timing between the exhaust period and the admission period, or minor changes in the size, form and construction of the various parts may be made and substituted for those herein shown without departing from the spirit of my invention, the scope of which is set forth in the appended claims.

I claim as my invention:

1. In an internal combustion engine, a compression clearance chamber, a combustion cylinder and a pair of piston valve cylinders, the chambers of the three cylinders being formed in common with the compression clearance chamber, pistons arranged for reciprocatory movement within the three cylinders, three cranks of the engine, the piston of one of the three cylinders being connected to each of the three cranks, exhaust ports formed in the intermediate portion of the combustion cylinder where it is uncovered when the piston within said combustion cylinder is at the crankward end of its stroke, charge admission ports formed in a second cylinder of the three cylinders, the crank to which the piston of the cylinder having the exhaust ports is connected being rotatively disposed in advance of the crank to which the piston of the cylinder having the charge admission ports is connected, the crank to which the piston of the third cylinder is connected being disposed rotatively diametrically opposite the crank to which the piston of the cylinder having the admission ports is connected, the dimensions of the said two oppositely disposed cranks and the relative parts attached thereto being respectively alike.

2. In an internal combustion engine, a combustion cylinder and a pair of piston valve cylinders, the chambers of the three cylinders being joined into a common chamber, one piston arranged for reciprocatory movement within each of the three commonly joined cylinders, ports formed in the combustion cylinder and one of the piston valve cylinders, the ports in the combustion cylinder being adapted to exhaust, the ports of the other of the two ported cylinders being adapted to fresh charge admission the exhaust port in the combustion cylinder being located at a point where it is uncovered when the piston in said cylinder is at the crankward end of its stroke, the stroke sweep of the piston of the cylinder having the exhaust ports providing gaseous compression and expansion alternately successively by the stroke movement of the respective piston of the said cylinder to the volume of the common combustion chamber, the stroke movement of the pistons within the remain-

ing two cylinders of the given three cylinder combustion unit providing gaseous compression and expansion synchronously to the volume of the said common combustion chamber.

3. In an internal combustion engine, a three cylinder combustion unit, a three cylinder combustion chamber, a piston arranged for reciprocatory movement within each of the three cylinders, means of imparting reciprocatory movement of continuous two stroke cycle time of fixed relation to the pistons of the said three cylinders, the stroke movement of one of the said three pistons providing alternately and uniformly a displacement variation to the three cylinder combustion chamber the wall of the cylinder within which operates the piston that provides alternate and uniform displacement variation being provided intermediate its ends with an exhaust port that is uncovered when the piston within said cylinder is at the crankward end of its stroke, the stroke movement of the two pistons within the remaining two of the three cylinders of a given combustion chamber being synchronously opposite.

4. In an internal combustion engine, a compression clearance chamber, three cylinders, the chambers within the said three cylinders being commonly joined by the said compression clearance chamber, one piston arranged for reciprocatory movement within each of the said three cylinders, means of associating the three pistons in fixed stroke time relation, one of the three pistons being of large stroke sweep displacement, the remaining two pistons being of small stroke sweep displacement, the stroke sweep displacement of the said two pistons having small stroke sweep displacement being equal, exhaust ports formed in the cylinder the piston of which is of large stroke sweep displacement which exhaust ports are arranged so that they are uncovered only when the piston within said cylinder is at the crankward end of its stroke, admission ports formed in one of the remaining two cylinders of the said three cylinders commonly joined by the said compression clearance chamber, the stroke movement of the piston of large stroke sweep displacement being of the cylinder having the exhaust ports being in advance with respect to the stroke movement of the piston within the one of the remaining two cylinders having the admission ports and the stroke movement of the two pistons having small stroke sweep displacement being synchronously opposite in direction.

5. In an internal combustion engine, a compression and expansion cylinder, a piston arranged for reciprocatory movement within the said cylinder, exhaust ports formed in the said cylinder at a point where

- they are uncovered only while the piston within said cylinder is at the crankward end of its stroke, two auxiliary cylinders, the chambers of the compression and expansion 5 cylinder and the chambers of the said two auxiliary cylinders being joined by a common clearance chamber, inlet ports formed in one of the said two auxiliary cylinders, a piston arranged for reciprocatory movement within each of the said two auxiliary cylinders, the stroke movement of the piston within the cylinder having the exhaust ports being adapted to effect the common displacement volume of the said three cylinders, the 10 stroke movement of one of the two pistons of the two auxiliary cylinders being adapted to effect an inlet valvular function to the said common chamber of the said three cylinders, the stroke sweep displacement of the two 15 pistons of the two auxiliary cylinders being equal, the stroke movement of the two pistons of the two auxiliary cylinders being synchronous in opposite direction, means of maintaining a fixed timed stroke relation between the three pistons of the said three cylinders forming a given common chamber, and ignition means located in the common 20 clearance chamber directly headward of the cylinder having the inlet ports.
- 30 6. In an internal combustion engine, a two stroke cycle combustion unit of three cylinders, a piston arranged for reciprocatory movement in each of the three cylinders, exhaust ports formed in one of the three cylinders at a point where they are uncovered only while the piston within said cylinder is at the crankward end of its stroke, inlet ports formed in a second cylinder of the three cylinders, a gaseous clearance 35 chamber formed of the engine, the said gaseous clearance providing a common clearance chamber for the piston stroke sweep displacement of each of the three cylinders, the reciprocatory movement of the piston within the cylinder having the exhaust ports providing compression and expansion to the gaseous charge of the engine and valvular function to the said exhaust ports, the reciprocatory movement of the piston within the cylinder having the inlet ports providing inlet port registration with the said gaseous clearance chamber of the engine, the reciprocatory movement of the piston within the third cylinder providing 40 synchronously a counterbalance of reciprocatory weight inertia and stroke sweep displacement exactly equal in value the reciprocatory weight inertia and displacement of the respective stroke sweep of the piston of the cylinder having the inlet ports.
- 45 7. In a two stroke cycle internal combustion engine, a power cylinder, a clearance chamber to the chamber of the said cylinder, a piston arranged for reciprocatory movement within the said cylinder, exhaust ports formed in the wall of the said cylinder at a point where they are uncovered only while the piston within said cylinder is at the crankward end of its stroke, a pair of cylinders formed to the side of the said power cylinder, a lateral extension of the said clearance chamber, the said lateral extension communicating with each of the chambers of the said pair of cylinders, inlet ports formed in the wall of one of the said pair of cylinders, pistons arranged for reciprocatory movement within each of the said pair of cylinders, the piston within the one of the said pair of cylinders having the inlet ports providing a valve means to the said inlet ports, the piston within the other of the said pair of cylinders providing a counter-stroke sweep displacement of equal volume to the stroke sweep displacement of the piston of the one of the said pair of cylinders having the inlet ports, three cranks of the engine to which the pistons of the said three cylinders are separately connected, means of maintaining the stroke movement of the three pistons in fixed stroke time relation and the arrangement whereby the crank to which the piston within the cylinder having the exhaust ports is connected is relatively rotatively disposed in advance of the crank to which the piston within the cylinder having the inlet ports is connected providing exhaust port opening and closing lead to the time of inlet port opening and closing.
- 50 8. In an internal combustion engine, three cylinders, a common compression clearance chamber joining the said three cylinders, one of said three cylinders being provided with inlet ports, another of said cylinders being provided with exhaust ports arranged so that they are uncovered only when the piston within said cylinder is at the crankward end of its stroke, pistons arranged for reciprocatory movement within each of the three cylinders, three cranks of the engine, each of the three pistons being separately connected to one of the three cranks, one of the cranks being arranged relatively rotatively in advance of the second crank, the third crank being arranged relatively rotatively diametrically opposite the said second crank and the stroke sweep displacement of the two pistons connected to the said second and third cranks which cranks are disposed diametrically opposite being of identical volume.
- 55 9. The combination in a two stroke cycle internal combustion engine, of a working cylinder, exhaust ports formed in the working cylinder, and located so that they are uncovered only when the piston within said working cylinder is at the crankward end of its stroke, a piston arranged for reciprocatory movement within the working cylinder, two auxiliary cylinders, inlet ports formed
- 60 65 70 75 80 85 90 95 100 105 110 115 120 125 130

in one of the said two auxiliary cylinders, a gaseous clearance chamber common to the chambers, the working cylinder and the two auxiliary cylinders, of the reciprocatory 5 stroke sweep displacement of the two pistons of the two auxiliary cylinders being equal, the stroke sweep displacement of the pistons of the auxiliary cylinders being less volume than the stroke sweep displacement 10 of the piston of the working cylinder, of the reciprocatory movement of the two pistons of the two auxiliary cylinders being synchronously opposite in direction, the reciprocatory movement of the piston of the work-

ing cylinder being in stroke position relatively in advance of the stroke position of the piston of the two auxiliary cylinders in which cylinder the inlet ports are formed, means providing a timed stroke relation of reciprocatory movement between the working piston and the two pistons of the two auxiliary cylinders and ignition means located in the wall of the clearance chamber directly adjacent the cylinder in which the inlet ports are formed. 15 20 25

In testimony whereof I affix my signature.
